DEFROSTER FOR REFRIGERATOR
EVAPORATORSDonald J. Lanker, Lima, Ohio, assignor to Art-kraft Manufacturing Corporation, Lima, Ohio
a corporation of Ohio

Application July 5, 1951, Serial No. 235,233

6 Claims. (Cl. 62—4)

1

This invention relates to defrosting of refrigerator evaporators and in particular to the automatic defrosting of refrigerator evaporators.

It is an object of this invention to produce a defrosting mechanism for the evaporator of a refrigeration system which is efficient in operation, of simple structure, and which can be readily adapted to any refrigeration system without altering the system.

This invention also contemplates a defroster of the above type which is dependable and substantially free of service trouble.

The present invention contemplates a method and arrangement for defrosting a refrigerator evaporator which utilizes hot gaseous refrigerant in the system to defrost the evaporator during the normal operation or refrigerating cycle of the refrigerating system.

In the drawings:

Fig. 1 shows a mechanical refrigeration system provided with the defrosting mechanism which is the subject of this invention, and in Fig. 1 the evaporator is shown in rear elevation.

Fig. 2 is a detail showing the heating element positioned within a coil of the refrigerant conducting tube.

Fig. 3 is an electric circuit diagram showing the defrosting mechanism connected into the electrical circuit for the refrigerating system.

Fig. 4 is a horizontal section through the evaporator taken along the line 4—4 of Fig. 1.

Fig. 5 is a detail sectional view of one of the evaporator plates along the line 5—5 of Fig. 4.

Fig. 6 is a section along the line 6—6 of Fig. 4.

Referring more particularly to the drawings there is shown for purposes of illustration a mechanical refrigeration system of conventional design comprising a motor compressor 1, a condenser 2 connected by a capillary restrictor tube 3 with an evaporator 4. The return suction or low pressure line from the evaporator to the compressor is designated 5.

The evaporator, for purposes of illustration, is shown as a three plate type comprising lower plate 6, center plate 7 and top plate 8. Each plate comprises an upper sheet 9 and a lower sheet 10 of aluminum or other high heat conducting metal which are riveted to each other and to the side wall 11 of the evaporator by rivets 12 (Fig. 5). The capillary restrictor tube 3 connects into a larger metal tube 13 which is sandwiched between plates 9 and 10 in each of the shelves 6, 7 and 8 and extends back and forth within the plates as shown in Fig. 4. From the

2

uppermost plate the refrigerant passes into an accumulator dryer 14 which connects into the suction line 5.

The evaporator tube 13 is formed into a helical coil 15 just preceding the point at which the tube 13 enters the lower plate 6. The evaporator tube 13 is also shaped into the form of a helical coil 16 where it runs from the outlet 17 of lower plate 6 to the inlet 18 of middle plate 7. Evaporator tube 13 is also formed into a helical coil 19 where it runs from the outlet 20 of middle plate 7 to the inlet 21 of top plate 8. The helical or spiral coils 15, 16 and 19 of the tube 13 facilitate mounting of the heating elements 22 in heat exchange relation with the refrigerant in the system. Whatever the form the evaporator may take, the important point is that of heating the gaseous refrigerant while it is passing through the evaporator.

20 Capillary tube 3 is shown only by way of example as one known means for separating the high compression side of the refrigeration system from the low compression or suction side and since the refrigerant passes into the low pressure

25 side of the system upon entering tube 13, it is understood that the tube 13 and coils 15, 16 and 19 form a portion of the evaporator the same as the portion of the tube 13 within each of the plates 6, 7 and 8 although, of course, the main refrigeration effect is produced in plates 6, 7 and 8.

30 Since it is proposed to heat the refrigerant within the evaporator during the normal cycling of the refrigeration system, that is, while the compressor is running, electrical heating elements 22 are mounted within each of the coils 15, 16 and 19 in heat exchange relation therewith. Each electrical resistance heating element 22 is of a conventional type and consists of a stainless steel sheath 23 in which is housed the electrical resistance element or wire 24 and insulated from the sheath by magnesium oxide 25 or other suitable insulator. The leads to each of 35 the heating elements 22 are designated 26 and 27.

35 The electrical circuit diagram is shown in Fig. 3. TM designates a conventional timing motor which is connected with a 110 volt source of electricity L1 and L2. C is the thermostatically operated cold control switch 22. TM1 and TM2 are switches which are opened and closed by timer motor TM. Each of the heating elements 22 is connected in parallel into the 110 volt electrical system L1 and L2 and are controlled by

a timer motor switch TM1. For purposes of illustration, there is shown a heating element 22 for each of the coils 15, 16 and 19. If desired, a heating element can be provided only for coil 15 ahead of bottom plate 6 but the provision of additional heating elements in coils 16 and 19 expedites the defrosting operation.

The operation of the defrosting mechanism is as follows: When the cold control switch C is closed and calling for refrigeration, then motor compressor unit 1 is opened and the refrigerant flows from motor compressor 1 into condenser 2 and thence through capillary tube 3 and into the spiral coil 15, then through plate 6, coil 16, plate 7, coil 19, and upper plate 8 into the accumulator 14 and thence through line 5 back to the intake side of the compressor. This is a conventional refrigeration cycle.

The timing motor is set so that after the refrigerator has operated any selected period of time such, for example, as twelve or twenty-four hours, the timing motor TM will close timer switches TM1 and TM2 and electrical current will now flow through each of the resistance heating elements 22 and the motor compressor unit will be set in operation irrespective of whether cold control switch C is closed or open. The timing device TM, TM1, TM2 is set so that it will cut on the electric current through the heating elements 22 and motor compressor unit 1 for a selected period of time such, for example, as eight to ten minutes.

It is important that the compressor 1 should be running while the current is flowing through the heating elements 22 so that the heating effect of the elements 22 will be quickly transmitted throughout the evaporator and melt the frost thereon. The heating element 22 in lower coil 15, which is preferably the main heating element having the largest wattage, say, for example, 300 to 400 watts, overcomes the refrigeration effect of the refrigerant within the coil and starts warming the refrigerant flowing through the bottom plate. The resistance element 22 within coil 16 has a lower wattage, say, for example, about 200 watts, and the heating element within coil 19 has a lower wattage of say, for example, about 100 watts. The heating element 22 within the coil 16 further warms up the refrigerant so that it does not condense in this coil 16 or in middle plate 7. The heating element within the third coil 19 also heats up the refrigerant further so that it will not condense in the coil 19 or in the top plate 8. The heat transmitted from the heating elements 22 to the refrigerant is in turn transmitted through the walls of the evaporator to the frost on the evaporator and quickly melts this frost. At the end of the defrosting cycle, timer motor switch TM, TM1, TM2 opens, cutting off the current through the timer motor switch to motor compressor unit 1 and heating elements 22. The operation of the refrigeration system is now controlled by the thermostatic cold control switch C.

The heating elements 22 slide into the coils 15, 16 and 19 and can be removed very readily. Preferably the heating elements 22 contact the insides of coils 15, 16 and 19 around the entire circumference and have a snug fit therein. The heating elements 22 are all located on or in the low pressure side of the refrigeration system. If the heating elements 22 are removed, the refrigerator operates in a normal manner without any defrosting cycle.

From the above it is evident that the instant

defrosting mechanism defrosts the evaporator by heating the refrigerant within the system and utilizing the refrigerant as the medium for conducting or transmitting heat from an outside heating source to the evaporator and thence to the frost on the evaporator. In effect, the instant defrosting mechanism converts the evaporator into a radiator and the refrigerant into a heat transmitting medium during the defrosting cycle without in anywise altering the normal refrigerating operation or cycle of the refrigeration system.

The temperature to which the heating elements 22 rise can be varied. A safe temperature limit for the heating elements 22 is from 150 to 175° F., but the temperature of the heating elements will vary with the capacity of the evaporator.

If desired the timer TM, TM1 can control the heating elements 22 only and the thermostatically operated cold control switch C can be used to turn on the refrigeration mechanism or motor compressor. It is only necessary that the motor compressor should run simultaneously with the energization of the heating element or elements 22 but it is not necessary to start and stop the motor compressor simultaneously with the energization and deenergization of heating elements 22. In other words, it is not necessary in Fig. 3 that switches TM1 and TM2 close or open simultaneously, it is only necessary that they both should be closed during sufficient and overlapping periods of time to defrost the refrigerator. The heating elements 22 put more heat into the refrigerant than the refrigerant can absorb as it evaporates. The heating means (22) should be positioned in the low side of the system and a part or all of the heating means should be positioned adjacent the expansion means (capillary tube or expansion valve) that is, adjacent the point where the high side connects into the low side, so that all frost will be removed from the low side.

I claim:

1. In a refrigeration system of the type including an evaporator, a condenser, a fluid line connecting the condenser and the evaporator, and a restrictor in the fluid line between the condenser and evaporator, the fluid line leading into the evaporator from the restrictor being in the form of a helical coil, an electric motor driven compressor for compressing the refrigerant and circulating the refrigerant through the system and an electrical circuit for supplying current to said motor, a heating element positioned within said coil and in heat exchange relation therewith, a switch adapted to be connected into said electrical circuit to supply current simultaneously to said motor for running the same and current to said heating element to heat the same, said heater having sufficient capacity to convert the liquid refrigerant into a warm vapor whereby the heater overcomes the refrigeration effect and warms the gaseous refrigerant flowing through the evaporator sufficiently to defrost the evaporator.

2. The combination defined in claim 1 wherein the evaporator comprises a plurality of plates and the refrigerant lines leading to said plates from said restrictor take the form of helical coils and wherein the heating elements are positioned within said helical coils.

3. In a refrigerating system including an evaporator and an electric motor driven compressor for compressing and circulating the refrigerant through the system, a defrosting mechanism comprising a helical tubular coil in the low side of the system through which the refrigerant passes, and

a heating element positioned in said coil in heat exchange relation therewith for heating the refrigerant flowing through said coil, said heating element giving sufficient heat to the refrigerant to vaporize the refrigerant and overcome the refrigeration effect of such vaporization whereby to cause warm vapor to flow through the evaporator to thereby defrost the evaporator.

4. The combination defined in claim 3 including timer switch means adapted to be connected into the electrical circuits of said heating element and electric motor for closing the circuits through said motor and heating element at selected intervals of time and for a selected period of time and the heating element supplies heat to the refrigerant during the defrosting cycle.

5. In a refrigerating system including an evaporator and an electric motor driven compressor for compressing and circulating the refrigerant through the system, a defrosting mechanism comprising a helical tubular coil in the low side of the system through which the refrigerant passes, and a heating element positioned in said coil in heat exchange relation therewith for heating the refrigerant flowing through said coil, said heating element giving sufficient heat to the refrigerant to vaporize the refrigerant and overcome the refrigeration effect of the vaporized refrigerant

as it passes through the evaporator to thereby defrost the evaporator, said heating element having a snug sliding fit in said coil.

6. The combination claimed in claim 5 wherein the helical tubular coil is positioned in the low side of the system adjacent to the outlet end of the high side of the system.

DONALD J. LANKER.
